DESIGN FOR A DRESS

Elizabeth Shell, Festus, Mo.

Application February 17, 1939, Serial No. 83,032

Term of patent 3½ years

To all whom it may concern:

Be it known that I, Elizabeth Shell, a citizen of the United States of America, residing in Festus, county of Jefferson and State of Missouri, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific collar, tie, and vestee as shown.

I claim:

The ornamental design for a dress, substantially as shown and described.

ELIZABETH SHELL.
